UNITED STATES PATENT OFFICE.

MICHAEL H. TRACY, OF WORCESTER, MASSACHUSETTS.

ELECTRIC SHUT-OFF COCK.

1,085,646.

Specification of Letters Patent.

Patented Feb. 3, 1914.

Application filed April 28, 1911. Serial No. 623,940.

To all whom it may concern:

Be it known that I, MICHAEL H. TRACY, a citizen of the United States, residing at Worcester, in the county of Worcester, State 5 of Massachusetts, have invented a certain new and useful Improvement in Electric Shut-Off Cocks, of which the following is a specification, reference being had therein to the accompanying drawings.

10 This invention relates to shut-off cocks but more particularly to mechanisms adapted to permit the operation of these cocks at a considerable distance from the same.

Particularly in case of fire, it is often 15 important to shut off the supply of gas from a building but the usual location of the shut-off cock in the basement makes it very difficult for anyone not familiar with the premises to find the same. Manually operated cocks on the main supply pipe exterior to the building have heretofore sometimes been installed but these must necessarily be located on the line of the pipe which may enter the building at any point 25 and frequently it is impossible to have them placed on old pipes as the same were never located with any such idea in view.

The object of the present invention is to 30 permit the shutting off of the gas supply in any building from a controlling point located within or without the building irrespective of the location of the gas supply pipe.

This invention comprises an electrically 35 operated mechanism connected to the gas shut-off cock on the main supply pipe and wiring connecting this mechanism with a control point suitably located. The electricity can be furnished by batteries or a 40 magneto permanently connected to the wiring but the former method is not considered advisable as such batteries are not dependable and the device might be inoperative at the time when it was most needed.

45 The device is preferably constructed with means at the control point whereby a portable magneto box or other source of electrical supply may be quickly connected to the wiring by the operator and the supply of 50 gas shut off from the building. This control point should preferably be upon the outside of the building.

In the embodiment which will be described hereinafter the device has been particularly adapted for fire purposes but the 55 same may be readily modified by anyone

skilled in the art for use in connection with any fluid conducting pipes and with either permanent or portable sources of electrical supply.

One embodiment is shown in the drawings 60 in which:—

Figure 1 is a diagrammatical view of the invention complete. Fig. 2, section on line 2—2 of Fig. 3. Fig. 3, section on line 3—3 65 of Fig. 2. Fig. 4, inside view of cover, as will be described hereinafter. Fig. 5, section on line 5—5 of Fig. 2. Fig. 6, section on line 6—6 of Fig. 3. Fig. 7, front elevation of casing with the cover removed as 70 will be described hereinafter. Figs. 8, 9, 10 and 11, detailed views of portions of the device for controlling the operation of the shut-off mechanism, as will be fully described hereinafter.

75 Referring to the drawings: The two parts of the pipe 20 have their ends threaded to enter the correspondingly threaded ends 21 of the casing 22. This casing is similar to that found in the ordinary type of shut-off 80 cock but is provided with a cup shaped flange 23 which is concentric with the axis of the shut-off cock 23^a. Upon the outer end of the shut-off cock is the stem 24 upon the end of which is formed a cup shaped 85 cover 25 which is also concentric with the axis of the shut-off cock and the annular flange 26 is adapted to envelop a portion of the outer wall of the cup shaped member 23. In the chamber 27 in the cup shaped 90 member 23 is located a spring 28 of the type usually found in clock mechanisms. One end of this spring is secured to the cup shaped member or portion of the casing 23 and the other extremity passes 95 through the slot 29 in the stem 24 of the cock 23^a so that, when the cock is released, as will be described hereinafter, the cover member 25 and the cock will be rotated in the direction of the arrows shown in Figs. 5 100 and 7.

From the inner face of the cover member 25 project inwardly the flanges or shelves 30 on each of which are secured magnet spools 31 of wire such as are found in all the 105 ordinary types of electro-magnets. From this inner face also extends another flange 32 through an orifice in which passes the post 33 provided at its upper end with a cross bar 34 such as is found in electric 110 bells. About this post 33 is secured a collar 35 between the under face of which and the

shaft operates a spring 36 which yieldingly holds the cross bar 34 away from the magnet face on the spools 31. Extending upwardly from the bar 34 is a projection or catch which is adapted to act against the lug 38 on the inner face of the casing 23. On the inner wall of the casing is a similar lug 39 which is adapted to contact on its front face with a lug 40 on the inner face of the cover plate 25. The operating face of this lug 40 on the cover is preferably set a quarter turn away from the working face of the catch 37 and the face of the lug 39 which is adapted to act against the face of the lug 40 to limit the travel of the cock is preferably set a quarter of a turn beyond the normal position of the face of the lug 40 and it would thus be a half turn away from the face of the catch 37.

At the point of control which may be at any distance from the shut-off cock is placed a control box 41 which is adapted to be set into a wall with the plate 42 resting against the face of the wall. Through this plate are four apertures 43, 44, 45 and 46, as is best shown in Fig. 8 of the drawings, and opposite to these apertures are the terminal posts 47, 48, 49 and 50 respectively. To the terminal posts 47 and 48 are secured the extremities of the wires forming the circuit 51 which carry the current adapted to cause the magnet spools to draw downward the bar 34 and release the catch 37 from the lug 38. To the posts 49 and 50 are secured the extremities of the wires forming the circuit 52, one of the opposite ends of the wires being connected to the lug 39 and the other to the lug 40 so that, even when the posts 49 and 50 are electrically joined, as will be described hereinafter, the circuit is not complete until the lug 40 moves into contact with the lug 39.

In the form of the device in which the source of electrical supply is carried by the operator the latter is provided with a portable magneto box 53 into which enter the wires which are connected to the magneto and which are adapted to complete the circuits 51 and 52. These wires are shown as inclosed in a cable 54 having at its other extremity a plate 55, shown in Figs. 10 and 11 provided with plugs 56, 57, 58 and 59 which are respectively adapted to be pressed into the apertures 43, 44, 45 and 46 in the plate 42 to connect the circuits 51 and 52.

Having its mechanism within the magneto box or otherwise suitably located thereon and having the bell upon the outside of said box, is an electrical bell of the ordinary type in use and this bell is connected to the circuit 52 for reasons which will be stated in connection with the description of the operation of the device hereinafter. This portable construction for the controlling of the mechanism connected to the shut-off cock, is of a

type which is particularly adapted for use in case of fire and the object of making the source of electrical supply portable is that a single magneto box may be carried by the firemen and used at each building fitted with the device, making it unnecessary for each building to be supplied with one.

The operation of the device is as follows:—When it is desirable to close the shut-off cock, the plate 55 connected by the cable 54 to the magneto box 53 is placed in position with the plugs 56, 57, 58 and 59 respectively opposite the apertures 43, 44, 45 and 46 and these plugs are then forced into the apertures by the operator grasping the handle 60. As soon as the plugs 56 and 57 contact with the terminal posts 47 and 48 the circuit 51 is complete and the operation of the magneto by the handle 61 causes a current to flow through this circuit, magnetizing the spools 31, and releasing the catch 37 from the lug 38. As soon as this catch is released, the spring 28 causes the cock to revolve in the direction of the arrow shown in Fig. 5 carrying with it the cover 25 on which is the lug 40. As soon as this lug 40 comes in contact with the lug 39, the cock will be prevented from further revolving and this contact will complete the circuit 52, causing the bell in the magneto box to ring and thus notify the operator that the cock has shut off the passage of gas in the supply pipe.

After the device has been operated to shut off the gas, the mechanism connected to the cock can be returned to its normal position and the passage in the pipe opened by turning the cover against the action of the spring until the catch 37 snaps into place in rear of the lug 38. To facilitate this resetting of the device, the outer walls of the cover may be milled, as is shown in Fig. 3 of the drawings.

What I claim as my invention and desire to secure by Letters Patent is:—

1. In a device of the class described, a fluid supply pipe, a shut-off cock in said pipe; a casing connected to said pipe, a spring acting between said casing and said cock to operate said cock, a cover member secured to said cock, a catch movably mounted on said member and adapted to engage an opposing projection on said casing to normally retain said cock in a position to permit the passage of fluid through said pipe; and electro-magnets mounted on said member adapted to move said catch to release said cock.

2. In a device of the class described, a fluid supply pipe, a shut-off cock in said pipe; a casing connected to said pipe; a spring acting between said casing and said cock to operate said cock; a member fixedly mounted on said cock, a spring controlled catch slidably mounted on said member and

adapted to engage an opposing projection on said casing to normally retain said cock in a position to permit the passage of fluid through said pipe, electromagnets mounted on said member adapted to release said catch and permit the operation of said cock; and means for controlling the operation of said magnets.

3. In a device of the class described, a fluid supply pipe; a shut-off cock in said pipe; a casing connected to said pipe; a spring acting between said casing and said cock to operate said cock; a member fixedly mounted on said cock; a spring controlled catch slidably mounted on said member and adapted to engage an opposing projection on said casing to normally retain said cock in a position to permit the passage of fluid through said pipe; electromagnets mounted on said member adapted to release said catch and permit the operation of said cock; means for controlling the operation of said magnets; and an alarm adapted to operate upon the completion of the closing operation of said cock.

4. In a device of the class described, a fluid supply pipe; a rotatable shut-off cock in said pipe; a casing connected to said pipe; a spring acting between said casing and said cock to rotate said cock; a cover member fixedly mounted on said cock; a catch slidably mounted on said member and adapted to engage an opposing projection on said casing to normally retain said cock

in a position to permit the passage of fluid 35 through said pipe; electro-magnets mounted on said member adapted to release said catch and permit the rotation of said cock; means for controlling the operation of said magnets; and an electric alarm adapted to 40 operate upon the completion of the closing operation of said cock.

5. In a device of the class described, a fluid supply pipe; a rotatable shut-off cock in said pipe; a spring acting between said 45 casing and said cock to rotate said cock; a cover member fitting over the open face of said casing and fixedly mounted on the stem of said cock; a catch slidably mounted on said member and adapted to engage an op- 50 posing projection on said casing to normally retain said cock in a position to permit the passage of fluid through said pipe; electro-magnets mounted on said member adapted to release said catch and permit 55 the rotation of said cock; means for controlling the operation of said magnets, a lug on said casing for limiting the travel of said cock, and an electric alarm adapted to be operated by the contact of a portion 60 of said cock with said lug.

In testimony whereof I affix my signature in presence of two witnesses.

MICHAEL H. TRACY.
